UNITED STATES PATENT OFFICE.

FRANK L. FENN, OF SCHENECTADY, NEW YORK, ASSIGNOR TO GENERAL ELECTRIC COMPANY, A CORPORATION OF NEW YORK.

CEILING-SWITCH.

No. 839,462.

Specification of Letters Patent.

Patented Dec. 25, 1906.

Application filed July 13, 1903. Serial No. 165,313.

To all whom it may concern:

Be it known that I, FRANK L. FENN, a citizen of the United States, residing at Schenectady, in the county of Schenectady, State of New York, have invented certain new and useful Improvements in Ceiling-Switches, of which the following is a specification.

The present invention relates to electric cut-outs, and more particularly to that class of cut-outs known as "ceiling-switches," and has for its object to provide a highly-efficient switch of this class which shall be compact and of neat appearance.

The invention comprises an arrangement of a rotary snap-switch upon a suitable base with its axis parallel to the face thereof and provided with a ratchet and a pivoted actuating-lever, the whole mechanism having its parts so constructed and arranged that an inclosing shell of small dimensions may be placed thereover without interfering with the operation of the parts.

The invention will be readily understood by reference to the following description and the accompanying drawings, forming a part of this specification, in which—

Figure 1 is a right-end elevation with parts in section of a ceiling-switch embodying one form of my invention. Fig. 2 is a back side elevation thereof with the shell removed. Fig. 3 is a bottom plan with parts in section of the same; and Fig. 4 is a left-hand elevation of the bearing-frame.

The base 1 of the switch, which may be of porcelain or other suitable insulating material, is made in the form of a circular slab with a rabbet 2 in the lower surface near its periphery for the reception of the upper edge of the inclosing shell 3, and passing transversely therethrough are two countersunk holes 4 for the screws, whereby the switch may be screwed to the ceiling, and a larger cylindrical hole 5 for the passage therethrough of the retracting-spring. To the lower surface of the base are secured two binding-posts 6 and a bearing-frame 8. The binding-posts 6 are each provided with a downwardly-projecting spring-contact 7, adapted to engage with a co-operating contact on the rotating member of the switch. The bearing-frame 8 is made U-shaped and has journaled in its side arms parallel to the face of the base 1 a shaft 9 of the rotary member. The left-hand end 10 of the frame

8 is made detachable by means of screws 11 from the main part of the frame in order to facilitate the assembling of the parts, and in order to adapt it to serve as a stop-plate it is provided on opposite sides of the shaft 9 with inwardly-bent portions 12, which are apertured to form shoulders 13 for engaging the locking member 14 of the switch. The locking member 14 comprises two radial arms 15, each provided with an outwardly-projecting lug 16, which engages shoulders 13 of the stop-plate, and a central hub portion provided with crown-cams 17 at its outer end for engaging a transverse pin 18, carried by the shaft 9. A helical spring 19 surrounds the shaft 9 and bears at one end against the locking member 14 and is connected at the other end to a hole in the shaft, so that when the shaft is turned by the ratchet 25 in a clockwise direction the spring is tensioned and the locking member 14 drawn inwardly by the action of the pin 18 on the crown-cams 17 until the lugs 16 clear the shoulders 13 of the stop-plate, whereupon the locking member and parts associated therewith are carried through a quarter-revolution by the recoil of the spring.

The switch-blade 20 has its opposite ends bent back at right angles to engage the stationary contacts 7 and is carried in a block of insulation 21, loosely surrounding the shaft 9 and the locking member 14 and provided with recesses 22, in which the arms 15 are free to move longitudinally and by which the block is caused to rotate with the locking member. The ends of the block 21 are provided with metal washers 23 and 24 to protect them from wear.

The ratchet-wheel 25 is mounted on the shaft 9, between the right-hand arm of the frame 8 and the washer 23 on the revoluble block 21 and connected thereto by a transverse pin 26. A bent actuating-lever 27 is pivoted to the right-hand arm of the frame 8 at 28 and is built up of two pieces of sheet metal riveted together and bent outwardly near their inner ends to provide a transverse aperture 29 for the reception of a pawl 30 and a helical spring 31, which serves as a common retracting means for the lever and pawl. The pawl 30 is pivoted at 32 upon the lever 27 and provided near its pivot with an attaching-ear 33, to which the spring 31 is attached. The upper end of the spring

extends through the aperture 5 and engages a cross-bar 34 at the upper end of the aperture. In order to prevent the operative end of the pawl being drawn up to the dead-center in case of disarrangement or wear of parts, a projection 35 from the edge of the arm of the frame 8 is bent into the path of the pawl, as indicated in Fig. 1. The outer end of the lever 27 is provided with a hole 36, to which a pendent chain or cord may be attached.

The shell 3 is made from sheet metal into the form of a cup and provided with a lining 38, of suitable insulation, and a slot 39 at one side for the passage of the actuating-lever 27 and is held in place by a screw 40, which passes through the center of its ends and engages a tapped hole in the bearing-frame 8.

I do not wish to be restricted to the particular form or construction of parts shown and described herein, for it is apparent that they may be changed and modified without departing from my invention.

What I claim as new, and desire to secure by Letters Patent of the United States, is—

1. The combination of an insulating-base, stationary contacts secured thereto, a U-shaped bearing-frame mounted on said base and provided with stop-shoulders, a shaft mounted in the side arms of said frame parallel to the face of the base, a rotary switch-blade and means co-operating with said stop-shoulders for producing snap movement thereof mounted on said shaft, and ratchet means for actuating said shaft.
2. The combination of an insulating-base,

stationary contacts secured thereto, a bearing-frame mounted on said base and provided with a plurality of stop-shoulders, a shaft supported in said frame parallel to the face of said base, a switch-blade mounted upon said shaft, locking means connected to said blade and adapted to engage said stop-shoulders, a spring connected to said shaft for producing a snap movement of said blade, and a ratchet mechanism for actuating said shaft.

3. The combination of an insulating-base, a snap-switch provided with a ratchet and mounted thereon with its axis parallel to the face of said base, a pivoted lever provided with a pawl adapted to engage said ratchet, and a single spring for retracting said lever and holding said pawl in contact with said ratchet.

4. The combination of an insulating-base provided with a transverse aperture, a snap-switch provided with a ratchet and mounted upon said base with its axis parallel to the face thereof, a pivoted lever provided with a transverse aperture and a pawl adapted to engage said ratchet, and a spring extending through said transverse apertures in the base and lever and connected at its ends to said pawl and to a pin carried at the opposite side of said base.

In witness whereof I have hereunto set my hand this 11th day of July, 1903.

FRANK L. FENN.
